COMBINATION STARTING ELECTRODE

Dewey D. Knowles, Wilkinsburg, Pa., assignor to Westinghouse Electric & Manufacturing Company, East Pittsburgh, Pa., a corporation of Pennsylvania

Application October 21, 1936, Serial No. 106,791

6 Claims. (Cl. 250—27.5)

My invention relates to gaseous discharge devices, and especially a pool type of device in which an auxiliary electrode is utilized to establish an arc between the pool and a main anode.

5 An object of my invention is to produce an arc discharge type of device having the sensitive starting characteristic of a glow discharge type of device.

Another object of my invention is to eliminate 10 the requirement for glow tubes or other auxiliary means that have hitherto been necessary to fire the arc type of device.

Other objects and advantages of the invention 15 will become apparent from the following description in which the figure is a view, partly in cross section of a tube incorporating my invention, and partly of diagrammatic circuit connections thereto.

The arc type of tube has been utilized where 20 high peaks of current and long life are necessary. The common forms of such a device is a container having a vaporizable constructing material therein such as mercury or its amalgams that will vaporize and then recondense into its 25 liquid pool. Such a type of device requires auxiliary electrodes for initiating an arc between the pool and the one or more other main electrodes. The prior art contains several types of these starting devices. The most recent and most successful 30 of these auxiliary electrodes is the make-alive type in which a high resistance material such as carborundum or a composite or alloy of boron and carbide has its tip immersed in the pool of mercury. This type of device is designated by 35 the registered mark of "Ignitron". "Make-alive" is a term designating a material, generally of the high resistance material referred to, which is in contact with the cathode and causes a cathode spot at the beginning of each conducting half 40 cycle. While this type of device is especially adapted to have a very high surge capacity and rugged construction, yet it has the disadvantage that it is not as sensitive as might be desired for some uses.

45 Heretofore auxiliary tubes have been utilized to ignite this tube having the make-alive electrode therein. In firing the tube through the make-alive, these auxiliary tubes have to withstand for a few micro-seconds a peak current of 50 25 amperes under 100 volts or more pressure. Because of this high peak current, these tubes have to be constructed in large sizes, although the average current they carry is very small. Another difficulty with this pool type of device 55 is that it is not very sensitive in cool weather

because, due to its construction, no appreciable amount of heat is put into the device when it is started and the arc does not readily start with cold metallic vapor.

My invention, therefore, concerns with utilizing 5 a very sensitive auxiliary starting electrode or grid in combination with the make-alive electrode to provide this arc type discharge device with the sensitivity of the grid-glow type of tube.

10 In the figure of the drawing, a preferred type of tube is disclosed in which certain parts are enlarged for the sake of understanding clearly the invention. The tube, as illustrated, has a container wall 10 of glass with a pool 11 preferably of mercury and an upper chamber portion 12 containing the anode 13. Other types of container and the plurality and changed position of anodes may be utilized as disclosed in the 15 prior art.

20 A control grid 14 may also be present, if desired. A starting electrode is placed adjacent the pool of mercury and this type of starting electrode is preferably of the make-alive type 15 of a high resistance material which is more 25 particularly described in Patent No. 2,069,283 granted on the application of Joseph Slepian et al., Serial No. 626,866, filed July 30, 1932.

25 Heretofore it was necessary to provide a surge of current through this auxiliary electrode 15 to establish the arc discharge between the pool 11 and the anode 13. Inasmuch as the construction did not utilize any appreciable heating current, the tube had very low sensitivity in cold 30 weather.

35 My invention contemplates utilizing another sensitive auxiliary starting device in combination with the make-alive 15. I also desire to utilize such a device that will supply a certain amount of heat to the interior of the device in 40 order that there may be little difficulty in establishing the arc very quickly in the device. I have accordingly selected a hot cathode type of device for an auxiliary electrode and in particular the type of device which is described as a 45 cathode in the copending application of Erwin F. Lowry, Serial No. 97,978, filed August 26, 1936.

50 This auxiliary electrode 16 preferably comprises two leads 17 and 18 for the heating current extending through a wall or press 19 in the casting to the interior thereof. A filament 20 is connected to these leads in order to provide the heating energy. As disclosed, one end of this filament has a connection 21 extending through the insulating supporting base 22 to the filament 55

lead 18. The filament is preferably enclosed within a cylindrical casing or enclosure 23 having a top cover 24 with a restricted opening 25 therein. If desired, a second cylindrical tube 26 preferably surrounds the inner casing 23 for the purpose of utilizing the heat most efficiently within the container 23.

The container 23 and the radiation of the heat shield 26, if used, are preferably connected electrically together such as at 27. The make-alive 15 is most conveniently connected to the auxiliary cathode 16 by the connection 28 to the exterior casing. The filament 20 or the interior walls of the enclosure 23, or both, are preferably covered with an electron emitting coating such as the oxides of barium and strontium.

The cathode connection 30 and the anode connection 31 are connected to a load 32 and the exterior source of anode-cathode power 33 which may be of any suitable primary or secondary type of electrical energy.

In starting the device, a heating current is put through the leads 17 and 18 to produce electrons emitting from the interior of the enclosure 23 through the opening 25 to produce a glow discharge to the anode 13. The heating current and this glow discharge will raise the temperature of the mercury vapor in case the ambient temperature of the tube is cold. This glow discharge will take place at a very low current. The glow discharge will create a passage of current from the anode 13 to the auxiliary cathode 16 to the connection 28 and the make-alive 15 to establish a cathode spot on the pool 11 that will create, in turn, an arc discharge from the anode 13 to this cathode spot on the mercury pool 11. It will be noted that the make-alive 15 has a high resistance and this will contribute to cause a higher voltage drop in the path including the auxiliary electrode 16 and the make-alive 15 than in the path directly from the anode 13 to the surface of the mercury pool 11.

I have utilized the particular type of auxiliary electrode 16 in order to ensure that the discharge will very quickly change to the direct discharge between the anode 13 and the surface of the mercury pool 11. The electrons emitted from the oxide coating within the container 23 will very soon saturate the opening 25. In order to increase the current flowing through this opening 25, a higher electrical pressure will be necessarily applied to create a larger current through this opening. Stated in other words, this means that the discharge current will be readily established up to a certain value, depending upon the size of the opening 25, and that thereafter any rise of current will be accompanied by a rise in the voltage drop between the anode 13 and the auxiliary electrode 16. This rise in voltage

ensures that the discharge will transfer to the lower voltage drop path from the anode to the mercury pool.

As an example, I prefer to design the opening 25 so that the voltage drop rises when the current is approximately 10 to 20% greater than the firing current necessary for the firing current of the make-alive 15. This value gives the gradient necessary to transfer the discharge to the pool.

While I have disclosed a preferred embodiment of my invention, it is obvious that many modifications thereof are possible within the spirit of my invention. I accordingly desire that the following claims should have only such limitations as are necessitated by the prior art.

I claim as my invention:

1. A discharge device comprising a container, a plurality of electrodes including a pool of vaporizable material therein, a make-alive in contact with said pool, an enclosure having an electron emissive coating connected to said make-alive, said enclosure having a limited area for egress of electrons therefrom.

2. A discharge device comprising a container, a plurality of electrodes including a pool of vaporizable material therein, a make-alive in contact with said pool and a casing connected to said make-alive having a filament and an electron emitting coating therein.

3. A discharge device comprising a container, a plurality of electrodes including a pool of vaporizable material therein, a make-alive in contact with said pool and a casing connected to said make-alive having a heater and an electron emitting coating therein, said casing having a limited area for egress of electrons therefrom.

4. A discharge device comprising a container, a plurality of electrodes including a pool of vaporizable material therein, a starting electrode in contact with said pool, an enclosure having an electron emissive coating connected to said starting electrode, said enclosure having a limited area for egress of electrons therefrom.

5. A discharge device comprising a container, a plurality of electrodes including a pool of vaporizable material therein, a starting electrode in contact with said pool and a casing connected to said starting electrode having a filament and an electron emitting coating therein.

6. A discharge device comprising a container, a plurality of electrodes including a pool of vaporizable material therein, a starting electrode in contact with said pool and a casing connected to said starting electrode having a filament and an electron emitting coating therein, said casing having a limited area for egress of electrons therefrom.
